UNITED STATES PATENT OFFICE.

WARREN C. REES, OF SOMERVILLE, MASSACHUSETTS, ASSIGNOR, BY DIRECT AND MESNE ASSIGNMENTS, TO ASEPTIC SERVICE COMPANY, OF BOSTON, MASSACHUSETTS, A CORPORATION OF MAINE.

SANITARY WATER-CLOSET.

1,092,392.

Specification of Letters Patent.

Patented Apr. 7, 1914.

Application filed June 25, 1913. Serial No. 775,685.

To all whom it may concern:

Be it known that I, WARREN C. REES, a citizen of the United States, residing at Somerville, in the county of Middlesex and 5 State of Massachusetts, have invented new and useful Improvements in Sanitary Water-Closets, of which the following is a specification.

My invention relates to sanitary toilet 10 closets, and its object is to provide a seat which shall be concealed and protected in a casing when not in use, and which may be automatically brought into the proper position over the bowl when desired, together 15 with automatic means for feeding fresh sections of strip paper over the surface of the seat, and means for automatically returning the seat after use to its normal position within the casing. In all other 20 devices of a similar character the seat and some portion of the paper are at all times exposed; both are therefore subjected to the possibility of contamination, and the paper covering as well to accidental tearing or 25 wilful destruction by vandals.

The chief novelty of my invention resides 30 in the employment of a seat composed of two separate sections disposed on opposite sides of the bowl, each adapted to be automatically reciprocated between its position 35 within a compartment in the main casing, and the usual seat position over the bowl there to serve as one side of the seat. Thus I am able to provide a closet in which the 40 seat is never exposed, but, on the other hand, is concealed and protected in a casing at all times, except when it is desired to use the seat in addition to the bowl. The numerous 45 advantages of such an arrangement are obvious. Furthermore the reciprocating movement of the seat sides is utilized to draw fresh sections of strip paper covering from the reservoir roll over the surfaces exposed to contact with the body. The seat sections 50 may or may not be locked within the concealing compartments, and if locked, may or may not be automatically released as desired.

The peculiar adaptability of my device to 55 use as a pay closet in public places will readily appear from the most superficial examination of the principal features embodied. I do not limit myself to use only in connection with the paper covering, as my

device may where desired be used without 55 this feature, in which case the surface of the seat exposed to the body is protected by the casing whenever the bowl is used merely as urinal or as a receptacle for waste. The preferred form however for all public lavatories should include the seat covering feature. Nor do I limit myself to the use of paper as the material for the covering when that feature is employed; any substance adapted to protect the body from direct contact with 60 the seat surfaces is claimed to be within the scope of this invention.

In the accompanying drawing, in which like numerals represent like parts in the various figures thereof, Figure 1 is a plan view 70 partly in section exposing a portion of the right side mechanism. Fig. 2 is a section on line 2—2 of Fig. 3 showing the right side reciprocating mechanism, part of which is also shown in dotted position. Fig. 3 is a 75 front elevation partly in section showing the right side of a bowl and the right side of my device attached thereto with the front casing plate removed. Fig. 4 is a section showing the left side mechanism in the seat 80 position. Fig. 5 is a detailed section on line 5—5 of Fig. 3 with casing broken away. Fig. 6 is a detailed perspective of the rocker arm 11 and lever 16. Fig. 7 is a detailed section elevation on line 7—7 of Fig. 3 showing 85 the release plunger. Fig. 8 is a detailed section on line 8—8 of Fig. 4 showing a portion of the take-up spool rotating mechanism.

Referring to the drawing, 1 represents an 90 ordinary water closet bowl.

2 is the casing, inclosing and supporting the mechanism of my device, hung from the main frame 3 which is secured to the bowl in any suitable manner.

4 is the compartment in the casing 2 which 95 conceals the right side seat section 5 when not in use. This compartment also serves to conceal and protect the right side paper feeding and reciprocating mechanism.

6 is a slot in the seat section 5, which 100 engages a rod 7 one extremity of which is secured to the front and the other to the rear of the casing 2 thus limiting the extent of the reciprocation of the seat section 5.

8 is a foot treadle adapted to actuate the 105 mechanism of both sides simultaneously, suspended from the crank 9 on the rock shaft 10 journaled in bearings in the casing 2.

Rigidly secured to the right extremity of the shaft 10 is the rocker arm 11 which is coupled at its further extremity to one end of the lever 16 by the connecting piece 14. The elbow connection thus formed permits of the unimpeded passage of the strip of used paper 17 from the seat section 5 to the take-up spool 44 between the rocker arm 11 and the lever 16.

Referring to Fig. 2, the opposite extremity of the lever 16 is connected by the ball and socket joint 18 with the lower end of the driving rod 19, pivoted at its upper end to the right side of the seat section 5 at 12. 20 is a lever, one end of which is pivoted at 21 to the bracket 22 secured to the casing, and connected at its other extremity by the ball and socket joint 23 with the lower end of the driving rod 24 pivoted at its upper end 20 to the left side of the seat section 5 at 13. The lever 16 carries a pin 25 which slidably engages a slot 26 in the lever 20; the levers 16 and 20 thus form a "scissors" movement which operates to reciprocate the driving rods 19 and 24. 27 is a spiral spring connected at one extremity with a projecting arm 28 on the lever 16, and at the other with a similar projecting arm 29 on the lever 20; this spring serves to draw the arms 28 and 29 toward each other and thus withdraw the seat section 5 from the position over the bowl to its normal position within the compartment 4. 30 is an arm projecting downward from the lever 16, and pivoted at its lower end to the outer extremity of the piston rod 31 of the air check chamber 32 pivoted at 33 to the bracket 22. The function of this air chamber is to prevent "racing" the reciprocation of the "scissors" movement, and consequent shock and undue wear and tear to the general driving mechanism of the seat section. 34 and 35 are trap doors in the casing 2, hinged respectively at 34^a and 35^a, which are automatically opened 45 during the movement of the seat section 5 from its position within the compartment 4 to the seat position over the bowl, and automatically closed during the retreat of the seat section to the normal position within 50 in the compartment. The mechanism for opening and closing the trap door 35 consists of the sprocket 65 fixed to the hinge shaft 35^b of the door 35 and protected by the housing 37 raised from the casing, the sprocket chain 66, the belt 69 and the spiral spring 67. The spring 67 is secured at its lower extremity to the casing at 68; to the upper extremity is secured one end of the chain 66 which passes over the sprocket 65 60 and is secured at its other end to one extremity of the belt 69. The belt 69 passes over the guide pulley 70 mounted in bearings on the bracket 22, and is secured at its other extremity to the arm 29 on the lever 65 20. Thus the tension of the spring 67 on the

one hand and the pull of the arm 29 on the other tend respectively to open and close the door 35. The door 34 is forced open by the pressure of the seat section 5 as the latter swings down to the seat position and is automatically closed during the retreat of the seat section by the action of a torsion spring 36 one end of which is secured to the door, the other to the casing.

The device which serves the double purpose of locking the driving mechanism against operation, and locking the seat section 5 in the position over the bowl, consists of the following parts: Referring to Fig. 7, 38 is a horizontally disposed rock shaft supported in the trough bearing 71 secured to the main frame 3 at 72. 73 is a vertically disposed curved lever fixed at a point between its extremities to the right end of the shaft 38, carrying near its lower end a shoulder 74 adapted to engage the under side of the projecting pin 75 on the rocker arm 11 and prevent depression of the rocker arm, thus locking the entire driving mechanism of the seat sections against operation. 76 is a forwardly projecting button secured to the upper extremity of the lever 73 by which the lever may be thrown and the driving mechanism unlocked. 77 is a spiral spring, secured at one end to the casing at 78 and at its other end to the lever 73 at a point below the bearing 71, which tends to hold the lever 73 in the normal position shown in Fig. 2. The lower end of the lever 73 is so constructed that it will engage the upper side of the pin 75 when the rocker arm 11 is depressed to the extreme point, and thus lock the seat section 5 in the position over the bowl. Fixed to the left end of the shaft 38 is the rearwardly projecting lever 79 pivoted to the lower extremity of the plunger 80. 81 is a housing for the plunger 80 supported on the bracket 82 secured to the main frame 3. 39 is a stop mounted on the housing 81 which serves as a support for the front edge of the seat section 5 when in the position over the bowl. The plunger 80, it will be noted, projects above the stop 39 so that the seat section 5 first comes in contact with the top of the plunger where it rests until further depressed by the weight of the occupant until the seat section rests on the stop; the lever 73 is thus thrown by the depression of the plunger, and the lower end disengaged from the pin 75, automatically releasing the seat section from its locked position over the bowl. 39^a is a stop formed integral with the raised back 3^a of the frame 3 which serves as a support for the rear edge of the seat section 5. 40 is a supply spool journaled in 115 bearings secured to the casing 2 and to the swinging arm 41, adapted to carry the roll of clean paper from which the fresh strip 42 is fed over the surface of the seat section 5 during the reciprocating movement of the 130

latter. 43 is a guide roll over which the fresh strip 42 passes from the supply spool to the surface of the seat section 5. 44 is the take-up spool journaled in bearings on the 5 casing 2 and the swinging arm 41, on which the strip of used paper 17 is wound automatically during the retreat of the seat section 5 from the position over the bowl to the position within the compartment 4. 45 is an 10 arm projecting from the ball and socket joint 18 to which is secured one end of the belt 46. From the arm 45 the belt 46 passes over the guide pulley 47, the pulley 48 rotatably mounted on the shaft 49 of the take-up 15 spool 44, the guide pulley 50, the idler 51, and the pulley 52 fast to the upper end of the spiral spring 53, and thence to the wall of the casing 2 where the other end is secured at 54. The function of the belt 46 is to 20 drive the take-up spool 44 during the retreat of the seat section. 55 is a ratchet rotatably mounted on the shaft 49 and fast to the pulley 48. 56 is a pawl carried on the take-up spool 44, adapted to engage the ratchet 55, 25 and thus rotate the spool 44 during the retreat of the seat section. 57 is a pawl pivoted at 59 to the casing 2 and adapted to engage the ratchet 58 secured to the take-up spool 44 and prevent unwinding rotation of 30 the latter. The spring 53 is secured at its lower end to the casing 2 at 60 in any suitable manner, and its tension maintains during the retreat of the seat section 5 a constant pull on the belt 46 with a resultant 35 tendency to rotate the spool 44 clockwise and take up any possible slack in the paper strip fed from the reservoir spool. The arm 41 is supported in the hinge 61 in the casing 2 and may be swung outward to permit of the 40 removal of used paper from the spool 44 and the substitution of a fresh roll on the reservoir spool 40. In its normal position the arm 41 is locked to the casing at 62 by the removable pin 63. 64 is a guide roll over 45 which the strip 17 of used paper passes from the seat section 5 to the take-up spool 44. The mechanism described is duplicated at the left of my device, differing only in lateral reversal of the relative positions of the 50 parts, the construction and functions remaining the same, and both sets of elements being actuated by common means, the treadle 8.

The method of operation is as follows: 55 When it is desired to use the seat the button 76 is pressed inwardly; the lever 73 is thus thrown and the shoulder 74 disengaged from the pin 75. This releases the driving mechanism from the locked position shown 60 in Fig. 2, and the foot treadle 8 may now be depressed. The depression of the treadle 8 to its extreme limit swings the crank 9 downward through an arc of approximately 60 degrees. This movement of the crank 65 is transmitted through the shaft 10 to the rocker arm 11 and thence through the connecting piece 14 to the lever 16, the extremities of which describe arcs of corresponding proportions, the left end (referring to Fig. 2) downward, the right end upward. As 70 the right end of the lever 16 is raised, the driving rod 19 is carried with it; simultaneously the pin 25 is brought to bear against the upper edge of the slot 26 in the lever 20, and the latter is swung upward on 75 its pivot 21, carrying with it the driving rod 24. As the driving rods 19 and 24 are raised, they force the seat section 5 vertically upward until the rod 7 engages the lower end of the slot 6. At this point the seat section 80 becomes a lever with the rod 7 the fulcrum, and the continued upward movement of the driving rods causes the upper end of the seat section to swing downward until it rests in the seat position upon the top of 85 the plunger 80. During this movement of the seat section from the position within the compartment 4 to the position over the bowl the doors 34 and 35 are opened in the following manner: As the lever 20 is raised, the arm 29 swings to the right (referring to Fig. 2) thus permitting the tension of the spring 67 to pull the chain 66 downward (referring now to Fig. 3) and impart a 90 clockwise motion to the teeth of the sprocket 95 65. The sprocket 65 being fast to the hinge shaft 35^b swings the door 35 open during the sprocket movement just described, which ceases when the seat section 5 reaches the position over the bowl and the arm 29 comes 100 to rest. The door 35 is then held in the open position until the seat section commences its retreat. As the seat section 5 swings from the vertical position down to the seat position, it comes in contact with 105 the door 34 and forces it to swing open on its hinge 34^a. As the foot treadle 8 is depressed to its extreme limit the pin 75 on the arm 11 passes beyond the lower extremity of the lever 73 which is then drawn 110 by the spring 77 over the pin 75 so as to engage the latter and lock the mechanism thus holding the seat section 5 in the position over the bowl. During the advance of the seat section 5 from the position within 115 the compartment 4 to the position over the bowl the pawl 57 in engagement with the ratchet 58 on the take-up spool 44 prevents unwinding rotation of the latter, and a fresh section 42 of clean paper is drawn from the 120 reservoir spool 40 over the surface of the seat section which is exposed to contact with the body of the occupant. The seat is now ready for use, the left side seat section having been simultaneously brought into its 125 proper position by the operation of the duplicate mechanism of the left side of the device, which as already stated is also actuated by the depression of the treadle 8. As the weight of the occupant is brought to 130

bear upon the seat section 5, the plunger 80 is depressed until the seat section rests on the position stop 39. The depression of the plunger 80 swings the lever 79 down thus 5 rocking the shaft 38 sufficiently to throw the lever 73 and disengage its lower end from the pin 75. This unlocks the mechanism, and the seat sections are now held in the position over the bowl only by the weight 10 of the occupant. As the occupant rises the spring 27 draws the arms 28 and 29 toward each other, the driving ends of the levers 16 and 20 are swung downward, carrying with them the driving rods 19 and 24 and consequently withdrawing the seat section 5 from the seat position to its normal position within the compartment 4. During the upward 15 swing of the seat section from the horizontal to the vertical position the door 34 is closed by the action of the torsion spring 36, while the door 35 is closed during the retreat of the seat section by the counter clockwise movement of the sprocket 65 actuated by the pull of the arm 29 transmitted through 20 the belt 69 to the sprocket chain 66.

The slack in the section of paper intervening between the reservoir spool 40 and the take-up spool 44 caused by the retreat of the seat section 5 is absorbed by the rotation 30 of the spool 44 which is actuated as follows: As the driving rod 19 descends, the arm 45 on the ball and socket joint 18 likewise descends, permitting the tension of the spring 53 to pull the belt 46, one extremity of which 35 is secured to the arm 45, over the idler 51, guide pulleys 50 and 47 and the pulley 48 fast to the ratchet 55. This movement of the belt 46 rotates the pulley 48 clockwise; the ratchet 55 being fast to the pulley 48 is 40 likewise rotated, and through the pawl 56 carried on the take-up spool 44 in engagement with the ratchet 55 this rotation is transmitted to the take-up spool and the used strip of paper is wound thereon. When 45 the slack in the strip 17 has been entirely absorbed and the paper becomes taut, the take-up spool ceases to rotate, and the belt 46 merely slips on the pulley 48 until the arm 45 reaches its normal low position shown in 50 Fig. 2. This belt slippage is utilized to compensate for the varying diameter of the roll of used paper on the take-up spool, and will be found to be a most efficient means for this purpose. As the arm 11 approaches 55 the limit of its upward movement the pin 75 engages the incline face of the shoulder 74 and slides into the position shown in Fig. 2, locking the device against operation until the mechanism is once more released by pressure on the button 76.

All the foregoing operations described with relation to the right side mechanism are simultaneously performed by the mechanism of the left side of my device which is as 60 stated identical in construction in every par-

ticular with the former, and actuated by the same means, the treadle 8.

What I claim and desire to secure by Letters Patent is:

1. In a sanitary toilet closet, the combination of a bowl, a reciprocating seat, a compartment adapted to receive said seat, and mechanism adapted to reciprocate said seat between a position over the bowl and its normal position within the compartment. 70

2. In a sanitary toilet closet, the combination of a bowl, a seat composed of a plurality of reciprocating sections, compartments adapted to receive said sections, and mechanism adapted to reciprocate said sections between a position over the bowl and their normal position within the compartments. 80

3. In a sanitary toilet closet, the combination of a bowl, a seat composed of a plurality of sections, compartments adapted to receive and conceal said sections, and mechanism adapted to reciprocate said sections between a position over the bowl and their normal position within the compartments, said mechanism embodying a lever provided 90 with a slot, and a lever provided with a pin adapted to engage said slot. 90

4. In a sanitary toilet closet, the combination of a bowl, a seat composed of a plurality of reciprocating sections, compartments 95 adapted to receive said sections, mechanism adapted to automatically reciprocate said sections between a position over the bowl and their normal position within the compartments, and mechanism adapted to automatically advance strips of paper over the surfaces of the sections. 100

5. In a sanitary toilet closet, the combination of a bowl, a seat composed of a plurality of reciprocating sections, compartments 105 adapted to receive said sections, mechanism adapted to automatically reciprocate said sections between a position over the bowl and their normal position within the compartments, mechanism adapted to automatically advance strips of paper over the surfaces of the sections, and a common actuating mechanism. 110

6. In a sanitary toilet closet, the combination of a bowl, a seat composed of a plurality of reciprocating sections, compartments adapted to receive said sections, mechanism adapted to advance the sections from their normal position within the compartments to a position over the bowl preparatory to use of the seat, means for locking the sections in the position over the bowl, and mechanism for automatically releasing and returning the sections from the position over the bowl to their normal position within the compartments after use of the seat. 120

7. In a sanitary toilet closet, the combination of a bowl, a seat composed of a plurality of separate reciprocating sections, 130

- compartments adapted to receive said sections, means for locking the seat sections within said compartments, mechanism adapted to release said seat sections, and 5 mechanism adapted to advance the seat sections from their normal position within the compartments to a position over the bowl preparatory to use as a seat.
8. In a sanitary toilet closet, the combination of a bowl, a seat composed of a plurality of separate reciprocating sections, compartments adapted to receive said sections, mechanism adapted to reciprocate said sections between their normal position with- 10 in said compartments, and a position over the bowl, and means adapted to advance a strip of paper over the surfaces of said sections, said means embodying a reservoir spool, a take-up spool, a belt adapted to ro- 15 tate the take-up spool, and a pawl and ratchet adapted to prevent unwinding ro- 20 tation of the take-up spool.
9. In a sanitary toilet closet, the combination of a bowl, a seat composed of a plurality of separate reciprocating sections, 25 compartments adapted to receive said sections, and mechanism adapted to reciprocate said sections between a position over the bowl and their normal position within the compartments, said sections being adapted to draw fresh strips of paper over their surfaces coincidentally with their reciprocation. 30
- In testimony whereof I have hereunto set my hand in presence of two subscribing witnesses, this 23rd day of June, 1913.

WARREN C. REES.
